COVERED HOT FOOD TRAY

Steven J. Cyr and Mark W. Whelan, Chippewa Falls,
Wis., and Kenneth L. Jones, Fullerton, Calif., assignors
to Standard Oil Company, Chicago, Ill.

Filed Aug. 25, 1969, Ser. No. 18,833

Term of patent 14 years

Int. Cl. D9—04

U.S. Cl. D9—185

Fig. 1

Fig. 2

*Fig. 3**Fig. 4**Fig. 5*

FIG. 1 is a plan view of a covered hot food tray showing our new design in fully open position looking at the internal surfaces;

FIG. 2 is a plan view thereof in a fully open position looking at the external surfaces;

FIG. 3 is a front elevation thereof in the closed position;

FIG. 4 is a side elevation thereof, the side opposite being a mirror image; and

FIG. 5 is a rear elevation thereof.

We claim:

The ornamental design for a covered hot food tray, as shown and described.
